UNITED STATES PATENT OFFICE.

LESTER B. WOOLEVER, OF AUSTINBURG, OHIO.

MILLSTONE-DRESS.

SPECIFICATION forming part of Letters Patent No. 291,010, dated December 25, 1883.

Application filed June 2, 1883. (No model.)

To all whom it may concern:

Be it known that I, LESTER B. WOOLEVER, a citizen of the United States, residing at Austinburg, in the county of Ashtabula and State 5 of Ohio, have invented certain new and useful Improvements in Millstone-Dress, of which the following is a specification, reference being had therein to the accompanying drawings.

This invention relates to an improvement in 10 millstone-dress; and it has for its objects to increase the number of lands and the cutting lines or edges of the furrows, and to increase the draft of the stone toward the skirt or outer edge of the stone, and thus enhance the grinding 15 capacity of the same, as more fully hereinafter specified. These objects I attain by a peculiar formation of the lands and furrows, as indicated in the accompanying drawings, in which—

20 Figure 1 represents a view of the face of the upper stone or runner, showing the same partially dressed according to my invention; and Fig. 2 represents a sectional view of the same.

The letter A indicates the millstone, the surface of which is formed with a series of sections or landings, B. The said sections are dressed, by means of a proper tool, in such manner as to form a series of tangential lands, D, and furrows E, the said lands and furrows 30 being of exactly equal width, as indicated in the drawings.

It will be perceived that by the improved dress true cutting-edges are formed, as indicated by the letter G, as above mentioned, and 35 by the general construction of the dress the capacity of the stone is increased and the grain is granulated and not crushed, as in the old style of dressing, as it is run against the cutting-edges G, instead of over them, thus reducing the tendency to burn, and making a 40 better grade of flour or meal than heretofore.

The lands and furrows being narrow, a greater number may be formed on the stone, and therefore more cutting lines or edges may be obtained, thus increasing the grinding capacity 45 of the stone. The lands and furrows being of equal width, the draft is equal all over the stone at any given distance from the eye; also, there are more furrow-lines as the skirt is approached, which greatly increases the capacity 50 of the stone, and as the draft increases directly as the capacity of the stone, therefore the draft is increased toward the skirt.

The operation of my invention is as follows: The upper stone or runner, in turning, crowds 55 the grain toward the skirt or outer edge—an operation technically known as the "draft" of the stone. The grain is ground by being driven over or against the sharp edges made by cutting grooves or furrows in the stone. 60 The more of these cutting-edges there are on the stone the greater its grinding capacity. Therefore, as there are more cutting-edges in my dress as the skirt is approached than in the ordinary dress, the capacity of the stone 65 is correspondingly increased.

Having thus described my invention, what I claim, and desire to secure by Letters Patent, is—

A millstone-dress having lands constructed 70 with flat horizontal faces and furrows formed of angular grooves, constituting a series of cutting-edges, increasing in number as they approach the skirt of the stone, the lands and furrows being of equal width from end to end, 75 substantially as and for the purposes specified.

In testimony whereof I affix my signature in presence of two witnesses.

LESTER B. WOOLEVER.
